This diagram is an exploded view of a mechanical assembly, possibly a clutch or flywheel assembly. The central component is a large circular part labeled 'C5'. On the left side, there is a hub assembly with a bearing labeled 'D2', a lock washer labeled 'D4', a lock nut labeled 'D40', a lock washer labeled 'D5', and a lock nut labeled 'D10'. On the right side, there is a similar hub assembly with a bearing labeled 'D3', a lock washer labeled 'D4', a lock nut labeled 'D40', a lock washer labeled 'D5', and a lock nut labeled 'D10'. Below the central circular part, there is a housing or frame labeled 'C2' on both the left and right sides. Inside this housing, there are several components labeled 'C1', 'C3', and 'C4'. A central vertical assembly is labeled 'A7', 'A8', 'A9', 'A10', and 'A8'. The diagram uses leader lines to point from the labels to the corresponding parts.

UNITED STATES PATENT OFFICE.

JOHN A. AMOS, OF CHICAGO, ILLINOIS, ASSIGNOR TO THE PYLE-NATIONAL COMPANY, OF CHICAGO, ILLINOIS, A CORPORATION OF NEW JERSEY.

CLASSIFICATION LAMP.

Application filed October 6, 1926. Serial No. 139,807.

My invention relates to improvements in classification lamps primarily electrically operated lamps used for classification and railroad signalling on lamps. A classification lamp is the lamp found on the front end of a locomotive to indicate the character of the train drawn by the engine. It is desirable to provide a lamp which may be easily attached and detached from the engine which will be firmly held in place without vibration wherein the color of the light may be easily changed and among the objects of my invention are provided such light. Other objects will appear from time to time throughout the specification and claims.

My invention is illustrated more or less diagrammatically in the accompanying drawings, wherein—

Figure 1 is an elevation of one side of the lamp;

Figure 2 is an elevation of the opposed side;

Figure 3 is a rear elevation;

Figure 4 is a vertical section; Figure 5 is a section along the line 5—5 of Figure 4 with parts in elevation and parts omitted;

Figure 6 is a section along the line 6—6 of Figure 4;

Figure 7 is a detail section showing the shutter support.

Like parts are indicated by like characters throughout the specification and drawings.

The base A comprises a generally circular flanged web, the downward portion of the web A¹ providing a base upon which the lamp may stand when not in use. The upper portion of the flange is tapered at A² to engage the tapered generally spherical housing A³.

A⁴ are lugs projecting from the base and A⁵ lugs projecting from the housing held together by a pivot bolt A⁶. A⁷ A⁷ are lock lugs projecting from the base A in opposition to lock lugs A⁸ projecting from the housing.

A⁹ is a lock screw pivoted on the lugs A⁷ associated with the lock nut A¹⁰ which engages the lugs A⁸ and clamps the housing rigidly and firmly in place upon the base A bringing the tapered flange A² into substantially air and water tight engagement with the flange A¹¹ on the lower side of the housing A³.

B is an electric light base mounted on the base A. In opposition to it are conduit sockets B¹ B² B³ threaded to engage either the end of a conduit or a plug, the arrangement being

such that the conduit may come in from any direction and be connected to the binding posts B⁴ B⁴ on the electric light base. The conduit sockets not being used will be closed by a plug B⁵. Projecting from the base A are bracket arms C, there being two of them spaced ninety degrees apart. These arms terminate in socket engaging plates C¹ adapted to engage the usual type of lamp socket on the locomotive or car. The opposed edges 60 of these plates C¹ are cut away as indicated so that contact on the socket takes place at the points C² C³ and somewhere along the inclined side C⁴ thus giving a three point contact between these plates and the sockets and holding the lamp firmly in position after it has once been mounted in the socket. C⁵ are bearing pads projecting from the outer wall 65 of the housing to give strength and furnish a point of contact where that is needed to 70 steady the support threaded by the plates.

On the two sides of the housing opposed to these bearing pads is an aperture as indicated at D to contain the lens D¹ which is held in place by guide holding rings D² seated by 80 means of screws D³. These lens of course are in line with the light source. Thus these lens are located on two adjacent sides of the housing, the axes of the beams being spaced 85 ninety degrees. D⁴ D⁴ are bosses diametrically opposed in the wall of the housing. They contain threaded therein bearing bushings D¹⁰ in which are mounted for rotation bearing pins D⁵. These bearing pins carry 90 the right angle shutters D⁶ pinned together at D⁷ and adapted when in one position to permit light from the light source to strike directly on the lens and when in the opposite positions shown in dotted lines to mask the light source or change the color as the case 95 may be. D⁸ D⁸ are stop members adapted to engage pads D⁹ on the shutters so that the shutters are held by gravity in the in or out position as the case may be. The pins D⁵ terminate in hand levers D¹⁰ whereby the 100 shutters may be manipulated from the outside.

The shutters comprise frames E with colored glass plates E¹ contained therein held in position by the spring loops E². The 105 shutters as previously indicated are pinned together at D⁷ by means of the lugs E³ and are mounted on the bearing pins D⁵ by means of the apertured boss E⁴ through which the split ends of these pins travel being held 110

against rotation by the holding pins E^5 whereby the parts are held together sufficiently to function as shutters without danger of binding or locking in operation owing to distortion of the housing, expansion and contraction.

10 Located on two adjacent sides of the housing beneath the lens D^1 are two switches F . Each of these switches controls the lighting of the lamp. The purpose of having the two switches is merely in order to insure that the lamp no matter how placed, can be easily and conveniently turned on or off. The switches are the ordinary turn switch comprising a hand member F^1 and a parallel member F^2 mounted for rotation in a sleeve F^3 and a flexibly mounted contact member F^4 engaging the conducting member F^5 of the electric light base.

20 I claim:

25 1. A lamp comprising a circular base having a tapered projecting annular flange, a closed housing having an open side adapted to be closed by the base, the wall of the side where it engages the base being tapered to engage the tapered surface on the base and means for holding the two surfaces together to make a dust tight closure, a light source mounted on the base and projecting into the 30 housing when in the assembled position.

35 2. A lamp comprising a circular base having a tapered projecting annular flange, a closed housing having an open side adapted to be closed by the base, the wall of the side where it engages the base being tapered to engage the tapered surface on the base and

means for holding the two surfaces together to make a dust tight closure, a light source mounted on the base and projecting into the housing when in the assembled position, said 40 means comprising a hinge connection between the housing and base at one side and an adjustable locking member interposed between the housing and base of the other side adapted when operated to draw the two together the housing being free to rotate on its hinge connection without interference with its light source.

45 3. In combination with a housing, a shutter for lights and the like comprising two frames, pivotally connected, translucent colored panels removably mounted in said frames, a separate pivot support for each of said frames, the two pivot supports being in line and projecting through the wall of the housing and means outside the wall of the housing for 50 rotating the frames in unison.

55 4. In combination with a housing, a shutter for lights and the like comprising two frames, pivotally connected, translucent colored panels removably mounted in said frames, a separate pivot support for each of said frames, the two pivot supports being in line and projecting through the wall of the housing and means outside the wall of the housing 60 for rotating the frames in unison, the frames being loosely pivoted together and loosely mounted on the pivot supports.

65 Signed at Chicago, county of Cook and State of Illinois, this 27th day of September, 1926.

JOHN A. AMOS.
